UNITED STATES PATENT OFFICE

ALBERT A. STRAUSS, OF PITTSBURGH, PENNSYLVANIA

LINEMAN'S BELT

Application filed April 3, 1929. Serial No. 352,269.

This invention relates to lineman's pole straps, window washer's safety belts and the like.

The pole straps used by linemen ordinarily consist of a strap of leather or the like having a snap hook at one end for attachment to one side of the lineman's body belt and an adjustable loop at the other end carrying a snap hook for attachment to the other side of the lineman's body belt. The loop adjustment is quite commonly made by means of an ordinary tongue provided buckle carried by the extremity of the belt and sliding on the strap between the two snap hooks, the portion of the strap on which the buckle slides being provided with suitable eyes for the tongue or tongues of the buckle. The strap is of course passed through a suitable loop on the second snap hook so that a loop is provided in the strap itself. There are two principal points of wear in such pole straps and one of these is at the point where the strap passes through the loop of the second snap hook. The other is at the point where the tongue or tongues pass through the eyes. In addition, such straps also wear at their central part where they pass around the pole in use. Obviously, breaking of the strap at any one of these points will tend to cause the lineman to fall. In like manner where such straps are used in window washing they are apt to break at the first two points and cause injury to the user.

The principal objects of the present invention are to provide an improved device of this character whereby breakage of the main strap member brings into service an auxiliary or safety member; to provide an auxiliary or safety strap member in such a device which under normal conditions of use will have no stress brought upon it so that it is free from the wear and strains of the main strap thereby of the device; and to provide a device of this character adapted for use by electrical linemen, window cleaners, parachute jumpers, structural steel workers, firemen and all people who are engaged in occupations utilizing devices of this nature.

With the above and other objects in view as will be hereinafter apparent, the invention will now be particularly described and claimed, reference being had to the accompanying drawings, wherein:

Figure 1 is a perspective view showing a lineman using the improved pole strap.

Figure 2 is a detail perspective view of the loop end of the pole strap illustrated in Figure 1.

Figure 3 is a perspective view showing the action of the safety member upon breakage of the main member of the strap.

Figure 4 is a plan view of a modified form of the strap in use.

In the invention as here illustrated there is shown the usual pole strap consisting of a leather or other main strap member 10 having one end passed through the loop 11 of a snap hook 12 and doubled back on the main part of the strap and secured as by riveting, sewing or any other suitable means. The other end portion of the belt 10 is passed through the loop 13 of a snap hook 14 and connected to this end is shown an ordinary two tongue buckle 15 which is thus slidably mounted on the portion of the strap 10 between the two snap hooks and adjacent the loop 13. Eyes 16 are provided for the tongues of this buckle so that an adjustable loop 17 is formed at this end of the strap by means of which the distance between the snap hooks along the strap may be regulated at the will of the user. This buckle 15 is preferably of greater dimensions than the opening in the loop 13 so that the buckle cannot pass through this loop.

In connection with the main strap there is provided a safety strap shown in Figures 1 and 2 at 18 and this safety strap has one end riveted or otherwise suitably secured to the outside of the main strap as indicated at 19. The strap 18 passes through the loop 13 on the outer side of the strap 10 and has its remaining end fixed to the outside of the strap 10 at a point beyond the end of the series of eyes 16 as at the point 20.

In the form shown in Figure 4 the construction is the same except that the strap

18 in this case is of sufficient length to pass entirely around the pole when used by a lineman, the attachment point 20 thus being close to the snap hook 12.

5 In each of these cases it is to be noted that the strap 18 is of greater length than the length of the strap 10 between the attachment points of the strap 18. By this means the strap 18 is normally slack and no stress 10 is brought on the strap under normal conditions of use so that the strap remains free from wear at all times. If, however, the main strap 10 wears sufficiently at one of its wear points to break or breaks at any 15 place from any cause then the strap 18 comes into play, the buckle 15 being pulled against the loop 13 as shown in Figure 3, and the new and unworn strap 18 takes the stress previously taken by the strap 10. It 20 will be noted that the points at which the strap 18 is attached to the strap 10 are points beyond which there is no wear under ordinary circumstances on the strap 10.

Having thus described the invention, 25 what is claimed as new, is:

1. A lineman's belt comprising in combination with a body belt, a main strap member for encircling a post or the like having adjusting means intermediate its ends, and 30 a safety member secured to the main member on opposite sides of the adjusting means and extending across the adjusting means.

2. A lineman's belt having in combination with a body belt, a main strap member provided at one end with means to secure said end to one end of the body belt, a buckle slidably mounted on the main member adjacent the remaining end, the end portion of the main member adjacent that 40 whereon the buckle slides being doubled on itself and having its extremity secured to the buckle whereby to form a loop in said member, means slidably mounted on the loop to secure the said main strap member 45 to the other end of said body belt, and a safety strap member extending across the buckle and having one end connected to the main member at one side of the buckle and the other end connected to the main member at the other side of the buckle.

3. A lineman's belt having a main strap member, a snap hook secured to one end of said main member, a second snap hook having a loop wherethrough the main member passes, a buckle carried by the remaining end of said 55 main member and slidable on said member between the snap hooks, said buckle forming a stop to prevent the belt end pulling through the loop, and a safety member consisting of a strap having one end fixed to the main member between the buckle and the first snap hook and its other end passed through the loop and fixed to the main member adjacent the buckle.

60 4. A lineman's belt having a main strap

member, a snap hook secured to one end of said main member, a second snap hook having a loop wherethrough the main member passes, a buckle carried by the remaining end of said main member and slidable on said member between the snap hooks, 70 said loop forming a stop to prevent the belt end pulling through the loop, and a safety member consisting of a strap having one end fixed to the main member between the buckle and the first snap hook and its other end passed through the loop and fixed to the main member adjacent the buckle, said safety member being of greater length than the length of the main member between the points of attachment of the safety member whereby the safety member is unstressed under normal conditions of use of the pole strap.

75 In testimony whereof I affix my signature. 80
ALBERT A. STRAUSS.
